(57) **CLAIM**

The ornamental design for a cupping device, as shown and described.

DESCRIPTION

FIG. 1 is a bottom front perspective view of a cupping device showing our new design;

FIG. 2 is a front elevation view of the cupping device of FIG. 1;

FIG. 3 is a back elevation view of the cupping device of FIG. 1;

FIG. 4 is a side elevation view of the cupping device of FIG. 1;

FIG. 5 is an opposite side elevation view of the cupping device of FIG. 1;

FIG. 6 is a top plan view of the cupping device of FIG. 1; and,

FIG. 7 is a bottom plan view of the cupping device of FIG. 1.

The broken lines depict portions of the cupping device that form no part of the claimed design.

1 Claim, 7 Drawing Sheets
